SILAS C. SALISBURY, OF NEW YORK, N. Y.

Letters Patent No. 88,082, dated March 23, 1869.

IMPROVEMENT IN REVERBERATORY FURNACES.

The Schedule referred to in these Letters Patent and making part of the same.

To all whom it may concern:

Be it known that I, SILAS C. SALISBURY, of the city of New York, in the county of New York, and State of New York, have invented certain new and useful Improvements in Reverberatory Furnaces; and I do hereby declare that the following is a full, clear, and exact description thereof, and of their mode, or manner of operation, reference being had to the accompanying drawings, and to the letters of reference marked thereon, and making a part of this specification.

The object of this invention is such a construction and arrangement of furnace as will most effectively secure the most complete consumption of the gases and combustible matter contained in the coal or fuel, and produce a more uniform temperature, and at the same time a more intense heat, as well as providing the means of desulphurizing the coal, and consuming that separated from the iron, thereby improving its quality.

Figure 1 is a general perspective view of the furnace.

Figure 2 is a vertical section, lengthwise, of fig. 1.

Figure 3 is a detached view, with a part broken away, showing the arrangement of the fire, or preparation and combustion-chambers.

Figure 4 is a bottom view of the grate, sliding plate, &c.

Figure 5 is a detached view of the outer plate of the fire-chamber.

The grate A is made of considerable depth or thickness, and is formed with numerous openings, or air-passages, *a*, so as to admit large quantities of atmospheric air through it to the bottom of the fire, and such air-passages are also distinct, or separate from each other, so as to divide the air thus admitted into numerous and comparatively small currents. I prefer to make the air-passages in the grate substantially as represented in fig. 4, largest in front, and decreasing toward the back end, and in a line with each other, as such an arrangement permits the grate to be cast in sections, as indicated by the dotted lines, and thus facilitates placing and removing it.

The furnace, consisting of two chambers, B and C, the former of which is the fire, or preparing-chamber, and the latter called the combustion-chamber, is constructed substantially as follows:

A heavy plate, or piece C, of cast-iron, from about half an inch to an inch in thickness, and extending back as far as the depth of the chamber A, forms the side outer walls of such chamber, and also its rear outer, as seen in fig. 3, such plate also extending upward about as far as the perpendicular sides of such chamber.

On the inner sides of such cast plate C, or made a part of it, is placed, at regular or suitable intervals, say every two inches, a series of pipes, or half-round tubes *b*, which are open at the bottom, to freely take in air, and closed at the top, to prevent the air passing through them, but having along their inner sides

a vertical series of holes, or perforations *c*, to allow the air to pass out from such tubes horizontally.

A section of one of such tubes *b*, with its open bottom-and-closed top, is shown in fig. 2, and a detached view of the same in fig. 5.

Within such cast or iron plate C, and in contact with the inner sides of the air-tubes *b*, is placed the fire-brick lining D, which makes the inner walls of the fire, or preparation-chamber A, and which should be from nine to twelve inches in thickness, the inner surface of such fire-brick being fluted, or formed with concave recesses, so as to prevent the fuel packing against the sides of such material.

Through such fire-brick, on every side of the fire-chamber A, is a series of perforations, or openings *d*, which correspond in position with, or connect with the perforations *c*, made in the inner sides of the air-tubes *b*. By means of such air-tubes *b*, perforated as described, and the corresponding perforations *d*, through the fire-brick D, air is continually supplied to the fire, or preparing-chamber A, and enters such chamber in divided jets, on every side of the burning fuel, both at or near the top thereof, and at different points below. Large quantities of air are thus not only constantly supplied to the chamber A, but by such arrangement of perforated tubes *d*, and perforated fire-brick, in combination with the grate, the air is presented to and distributed through every part of the burning fuel. The air supplied to the chamber A through the tubes *b*, also becomes highly heated by passing along the heated surface of the iron plate C, and through the fire-brick lining, and the chamber A is thus, in fact, continually supplied with a hot blast; and to assist in heating the air thus supplied, the tubes *b* may be filled with fine gauze cloth, made of asbestos, which, though continually hot, will not be consumed.

To such chamber A there is also admitted, by means of a pipe, *e*, extending under the mouths of the tubes *b*, and opening into the same by small perforations, or jet-tubes, and which pipe connects with any sufficient source of supply, steam or superheated steam, which becomes decomposed in passing into or on entering such chamber, furnishing additional oxygen and also hydrogen, and thereby assisting to effect a more complete and perfect combustion of the fuel.

By thus supplying the fire, or preparing-chamber on every side thereof, and on the top of and at different points in the burning fuel, with divided jets of heated air, and decomposed or decomposing steam, the decarbonization of the fuel commences, or is carried on from the top and from the outside of the mass of fuel, instead of principally from the bottom, and at the same time the intense heat penetrates the centre, and completely effects the same results there. The combustion being thus carried on most actively from the top and sides of the fire, the under surface of the grate-bars, notwithstanding the great intensity of the fire,

remains quite cool, comparatively. In an ordinary furnace, with a fire of the intensity easily and constantly maintained in my fire, or preparing-chamber, the grates-bars would be melted or burned out in a very short time.

The quantity of air and steam supplied to the chamber A, through the tubes b, may be regulated and varied by means of a sliding plate, E, so arranged that by its movement the mouths of such tubes b may be increased or diminished in size, and the supply of air and steam can be partially or wholly cut off, as desired, and the consumption of fuel can thus be regulated, according to circumstances.

The fire, or preparing-chamber A is wholly arched over and closed, as shown in figs. 2 and 3, with fire-brick, or some material capable of bearing a high heat without injury, and the enclosing walls and top of such chamber are pierced with numerous holes, or openings f, generally about half an inch in diameter, for the purposes hereafter set forth.

Above such preparing-chamber A is a chamber, B, which I call the combustion-chamber, and communication with such chamber from the chamber A is only by means of or through the holes, or openings f. The carbonic oxides and products of combustion formed in the interior, or preparing-chamber A, in passing through such openings f, are divided into numerous small jets, or currents, and enter the combustion-chamber B at many different angles, and thus are caused to come in more complete and intimate contact with, and are thus more effectually mixed with the jets, or currents of heated air and steam, which enter such combustion-chamber B, as well as the fire, or preparing-chamber A.

Such supplies of air and steam are furnished to the combustion-chamber through the spaces, or openings g, between the iron plate C and the fire-brick D, and the air-tubes b, (which, as before described, furnished air and steam to the chamber B.) A section of one of such spaces g, open at the top to allow the air and steam to pass through it, and into the combustion-chamber B, is shown in fig. 2. As before described, in connection with the fire-chamber A, the air supplied to the combustion-chamber becomes highly heated in passing thereto, and is, in fact, a continuous hot-air blast.

The steam-jets, supplied to such chamber by the pipe e, become also wholly or to a great degree decomposed, by contact with the highly-heated iron plate C and fire-brick D, and produce hydro-oxygen gases, and thereby increase the quantity of oxygen, and intensify the heat.

The air supplied to the combustion-chamber becoming highly heated while passing thereto, is rendered lighter than the carbonic oxides, which are continually pouring into such chamber from the fire, or preparing-chamber B, and an immediate chemical union and utilization of such gases of the coal and air and steam take place, and their complete and perfect combustion is produced.

The pressure and velocity of the steam escaping from the pipe also produces or causes an increased draught, and consequently an increased quantity of oxygen is carried in through the tubes b and supplied for combustion. Actual practical tests clearly demonstrate that such use of steam in the chambers A and B adds greatly to the economy produced or effected by the general combination.

The quantity of air and steam supplied to the combustion-chamber will also be governed and regulated by the sliding plate before described in connection with the fire-chamber.

The reverberatory furnace, except as to the particular construction and arrangement, as described, of the preparation and combustion-chambers A and B, is substantially like those in ordinary use. By such construction and arrangement of those chambers, I am enabled to produce a much more intense heat, and thus render the action of the furnace more effective, and also secure a more equable temperature, thereby rendering the action of the furnace more uniform, and producing better results.

What I claim as my invention, and desire to secure by Letters Patent, is—

1. In combination with reverberatory furnaces, the application and use of a heating-apparatus, or furnace, having an inner fire, or preparing-chamber, and an outer, or combustion-chamber, constructed and arranged substantially as described, and fitted with air-tubes and spaces between the walls of the fire-chamber, to supply heated air, or air and steam to both such chambers, and having the inner separated from the outer chamber by means of a perforated arch or top, substantially as and for the purposes set forth.

2. In combination with a reverberatory furnace, having a fire, or heating-apparatus constructed and operating substantially as described, the arrangement of the steam-pipe e, substantially as and for the purposes set forth.

SILAS C. SALISBURY.
